DESIGN FOR A COMBINED KEYHOLDER AND IDENTIFICATION DEVICE

Howard L. Moore, Cochranton, Pa.

Application January 13, 1945, Serial No. 117,412

Term of patent 7 years

(Cl. D17—14)

To all whom it may concern:

Be it known that I, Howard L. Moore, a citizen of the United States, residing at Cochranton, in the county of Crawford and State of Pennsylvania, have invented a new, original, and ornamental Design for a Combined Key Holder and Identification Device, of which the following is a specification, reference being had to the accompanying drawing, forming part thereof.

Figures 3 and 4 are end views.

The body, through which portions of a continuous key-holding chain slide, is formed of transparent or semi-transparent material and is recessed to receive an identification card insertible through the long opening in one end of the body. The opposite sides of the body are the same in appearance.

I claim:

The ornamental design for a combined key holder and identification device, as shown and described.

HOWARD L. MOORE.
